SAFETY CRANKING DEVICE FOR INTERNAL COMBUSTION ENGINES

Victor J. Murawski, Hannibal, Mo.

Application May 26, 1934, Serial No. 727,619

5 Claims. (Cl. 123—185)

This invention relates to internal combustion engines, and, more particularly, to means for manually cranking the same.

The principal object of the invention is the provision of new and improved means for automatically disengaging the crank from the crank shaft in the event the engine backfires while manually cranking the same.

Another object of the invention is the provision of a new and improved safety device for preventing injury to the operator in the event the engine backfires while being cranked and which is so constructed as to constitute an attachment that may easily and readily be applied to the engine.

A further object of the invention is the provision of a new and improved attachment for internal combustion engines that may be attached to existing structures with modifications therein.

A still further object of the invention is the provision of new and improved means for preventing an operator from becoming injured while manually cranking an engine in the event of backfiring, which is simple in construction, efficient in operation and that is inexpensive to manufacture and easily installed.

Other and further objects and advantages of the invention will appear from the following description taken in connection with the accompanying drawing, in which:—

Fig. 1 is a perspective view of a portion of an internal combustion engine with the radiator removed, for the sake of clearness, and parts broken away, showing the crank in position about to be attached to the crank shaft;

Fig. 2 is a front elevation of the engine with parts omitted for the sake of clearness, and with parts broken away;

Fig. 3 is a side elevation of the forward portion of the engine with parts broken away and showing a crank in the act of being applied for cranking the engine; and

Fig. 4 shows an elevation of the crank.

In the cranking of internal combustion engines by hand, there is always more or less danger of backfiring. This is principally due to failure on the part of the operator to retard the spark before cranking the engine, or to sufficiently retard said spark. But from whatever cause, the backfiring of the engine during the cranking operation often results in a broken wrist or arm—sometimes other serious injuries—to the operator.

It has been proposed to employ safety devices

of one kind and another. In some, the structure is so complicated as to be too costly to justify their use; others require changes in the engine structure or modifications of the crank shaft, while still others require a radical departure from the conventional crank mechanism for starting the engine.

The present invention seeks to avoid these difficulties by the provision of a simple device that will require no change in the engine structure and which will utilize the conventional means now employed for starting the engine.

Referring now to the drawing, the reference character 10 designates an internal combustion engine, having the gear case 11 for the cam shaft 10 gears on the front thereof, as is usual in such constructions. The crank shaft 12 is of the conventional type and extends through the gear case 11 in the usual manner.

The crank shaft is provided with the usual 20 cranking pin 13, which is adapted to be engaged by shoulders or clutch teeth 14 on a head 15 of the starting crank 16. In some engines, the crank shaft carries the clutch teeth and the crank carries the pin, but it is immaterial how these parts 25 are arranged. Since the parts thus far described are of the usual or well-known construction, it is not thought necessary to further illustrate or describe the same.

The mechanism for preventing the reverse 30 movement of the crank and for disengaging the shoulders or clutch teeth 14 from the pin 13 when the engine backfires comprises a ratchet member 17, which is rigidly secured to the engine by being attached to the front wall 18 of the gear case 35 11, as by means of rivets or tap screws 19, or other suitable means.

The ratchet member 17 is provided on its face with the ratchet teeth 21. The head 15 of the starting crank 16 is provided inwardly of the 40 shoulders 14 with an enlargement 22 which may be attached thereto or integral therewith. Preferably, though not necessarily, the enlargement 22 may be cast integral with the head 15. It has an annular face 23 extending at right angles to 45 the axis of the head. Pivotally secured in the enlargement 22 and adapted to extend outwardly beyond the annular face 23 of the enlargement are the pawls 24 and 25. These pawls are pivoted in the bottom of recesses 26 formed in the face 50 23 in any suitable manner, as by means of the pins 27. The rear walls of the recesses 26 are curved, as shown at 28, and the pawls are also curved and substantially conform to the curved wall 28. The outer ends of the pawls 24 and 25 55

are normally held outwardly beyond the face 23 of the enlargement 22 by spring means that will permit the pawls to ride over the teeth 21 during the cranking operation. While only two pawls 5 are employed, it is understood that the number is immaterial. In any event, they are so mounted on the crank head that they do not simultaneously disengage the ratchet teeth, thereby avoiding the probability of failure to engage the teeth in 10 case of backfiring.

As shown, coil springs 29 having their inner ends rigidly secured in recesses in the head 22 are employed for this purpose. The outer or free ends of the springs 29 are unattached to the 15 pawls, whereby the pawls are free to take the position shown in dotted lines in Fig. 3 for disengaging the crank when the engine backfires.

In the operation of the device, the starting crank is attached to the crank shaft 12, in the 20 usual manner, with the shoulders or clutch teeth 14 in engagement with the pin 13. Upon turning the crank for starting the engine, first one pawl and then the other will snap past the teeth 21, and, in the event the engine backfires, the pawls 25 will prevent the backward rotation of the crank.

Upon reverse rotation of the engine crank shaft, engagement of pin 13 and shoulders 14 causes the starting crank 16 to rotate reversely an infinitesimal amount, or just sufficiently to seat the free 30 ends of the pawls 24 and 25 in the spaces between ratchet teeth 21. Because the pivot pins 27 of the pawls are positioned appreciably behind the face 23 of the head 22, and the pawls extend therefore diagonally, the rotary impulse given 35 to the starting crank by the reversely rotating engine crank shaft, or, more strictly speaking, the rotary reaction of the ratchet member 17 against the pawl ends, does not act longitudinally of the pawls, but contains two components, a rotative 40 force and an endwise thrust. The pawls therefore pivot on their pins 27, turning out of the recesses 26, and act as levers for pushing the head 15 of the starting crank outwardly from the ratchet member. The length of the pawls and the depth 45 of the shoulders or clutch teeth 14 are so proportioned that when the pawls have acted through their full capacity to separate the members 17 and 15, the pin 13 is disengaged from the shoulders 14. This mode of operation is made clear in 50 Fig. 3, where dotted lines show one of the pawls in extended position consequent upon reverse rotation of the engine crank shaft, and where the extended pawl is shown projecting beyond the shoulder 14 sufficiently to assure disengagement 55 of the pin 13 from the shoulder upon full extension of the pawl.

In order that the device may be readily applied as an attachment to engines as at present constructed, the ratchet member 17 may be provided with diametrically extending slots 31 and 32 which form a continuation of the axial opening 33. It will only be necessary to drill holes through the front plate or wall of the gear case in order to secure the ratchet member in position, or on 60 some engines where the gear case is omitted, it may be attached directly to the cylinder block or other part of the engine.

In applying the ratchet member 17 to the engine, the plate or front wall 18 of the gear case 70 is tapped, after which the member 17 is slid onto the crank shaft 12 by turning the same to the position where the slots 31 and 32 are in alignment with the pin. The ratchet member is then secured in position by applying the tap 75 screws. In certain cases the ratchet member is

secured in position by rivets. In such cases, the gear case plate must first be removed.

It is thought from the foregoing taken in connection with the accompanying drawing that the construction and operation of my device will be apparent to those skilled in the art, and that changes in size, shape, proportion and details of construction may be made without departing from the spirit and scope of the claims hereunto appended.

I claim as my invention:—

1. In an internal combustion engine provided with a crank shaft extending outwardly from the engine, a ratchet rigidly secured in position and having an axial opening through which said shaft extends, a crank having a detachable connection with said shaft, and a pawl at opposite sides on said crank pivoted in recesses for engaging the teeth of said ratchet and adapted to cause the disengagement of said connection upon the backfiring of said engine.

2. A starting crank for internal combustion engines comprising a head having means for detachably connecting the same to the crank shaft of an internal combustion engine, an enlargement 25 on said head having an annular face in a plane normal to the axis of said head, a plurality of curved pawls pivotally mounted in recesses in said face and resilient means for normally projecting the free ends of said pawls beyond said face. 30

3. In an internal combustion engine, an attachment comprising a ratchet member having openings for receiving the fastening means for rigidly attaching the same to said engine and having an axial opening with diametrically opposite slots extending radially from said opening through which the crank shaft of an engine having radially extending studs are adapted to extend, and a starting crank having clutch teeth for engaging said studs and provided with spring-pressed pawls engaging said ratchet teeth, said pawls having their inner ends pivoted in recesses in said crank and movable to a position to disengage said clutch teeth from said pin. 40

4. An attachment for use on an internal combustion engine comprising a ratchet member having ratchet teeth on one face and provided with means for rigidly attaching the same to an engine, a crank having clutch teeth for turning a crank shaft of an engine, said crank having a portion provided with a plurality of recesses about its axis, pawls pivoted in said recesses and slidable over said ratchet teeth when said crank is moved in one direction and engaging said ratchet teeth and moving said crank axially outwardly when moved in the other direction. 55

5. In an internal combustion engine having a crank shaft provided at one end with a pair of oppositely arranged radially extending pins, the combination of a starting crank provided with a head having clutch teeth for engaging said pins, a ratchet member rigidly secured to said engine over said crank shaft and having a recess for receiving said head, an enlargement extending about said head outwardly thereof, said enlargement having a plurality of equi-angularly spaced recesses in its inner face, spring-pressed pawls pivoted at the bottom of said recesses, said pawls adapted to be received within said recesses to pass over said teeth while cranking the engine and to project beyond said recesses for disengaging said starting crank upon the backfiring of said engine. 60
